UNITED STATES PATENT OFFICE.

PAUL DANIEL, OF JAMAICA, NEW YORK.

CENTRIFUGAL PUMP.

1,156,063.

Specification of Letters Patent. Patented Oct. 12, 1915.

Application filed October 28, 1912. Serial No. 728,057.

To all whom it may concern:

Be it known that I, PAUL DANIEL, a citizen of the Republic of France, residing at Jamaica, in the county of Queens and State 5 of New York, have invented certain new and useful Improvements in Centrifugal Pumps; and I do hereby declare the following to be a full, clear, and exact description of the invention, such as will enable others 10 skilled in the art to which it appertains to make and use the same.

The present invention has relation to an improved form of bearing for rotary devices whose bearings ordinarily afford paths 15 for leakage of fluid under pressure, such, for instance, as centrifugal pumps. The improved bearing offers material and obvious advantages as over the ordinary stuffing box.

20 I have illustrated my invention in connection with a centrifugal pump, although the same is obviously applicable in other connections.

Figure 1 is a longitudinal section of one 25 form of my improvement and Fig. 2 is a similar view of a modification thereof.

As shown in the drawing the pump comprises a pump chamber having a substantially cylindrical portion and a conical portion 30 11, uniting therewith and preferably separable therefrom along a circular line, the two portions being firmly clamped together by means of the bolts 12. The fluid to be pumped is led to the chamber 11 by 35 means of any appropriate inlet pipe connected by means of the union 13 to the inlet nipple 14 which connects with the narrow end of the conical chamber 11. The opposite end of the cylindrical portion is provided with an outlet chamber 15 which communicates with the delivery pipe 16.

Within the chamber 11, is placed a rotary member which comprises the usual central shaft 17 provided with one or more vanes 45 18. In the form shown four of these vanes are used. The vanes in question diverge symmetrically from the shaft 17 and are preferably bent at their ends as shown at 50 19 so as to present a convex surface to the fluid as the rotary member revolves. The outer edges of the vanes are so disposed that each comprises a tapering portion and preferably a non-tapering portion is also provided so that in the preferred form these 55 outer edges are made parallel to the elements of the cone 11 and cylinder respec-

tively. These edges are preferably brought very close to the walls of the chamber.

The chamber is provided with a hollow stem 20 which serves to afford a firm support for the extension 21 of the shaft 17 by means of which the revolving member is rotated. In the drawing this is accomplished by means of the pulley 22 driven by a belt 23, but any well known means may be employed for this purpose.

In order to avoid the use of the stuffing box in connection with my device I prefer to employ the construction shown wherein a suitable bushing 24 closes the inner end of the stem 20 and against which bears a second bushing 25 provided with a conical seat. This latter is loose on the shaft. Behind the bushing 24, I place revolving thrusting bearing 26 which serves as a forward abutment for a spring 27 within the hollow of the stem 20, and the outer end of said spring bears upon a sleeve 28 firmly fixed to the shaft 21, as by means of the set-screw 29, so that the effort of the spring 27 acts 70 through the shaft 21 to cause the conical base of the shaft 17 to bear firmly upon the seat 25 on the bushing 24 and thus afford the necessary tight joint. I prefer to so arrange the vanes 18 that they will converge 75 to a point on the axis of revolution just within the inlet nipple 14.

The mode of operation of my device is as follows—The entering water meets the narrowest portions of the vanes 18, which are moving at a relatively low rate of speed and as the water advances it is influenced by a more and more rapidly moving portion of each vane. The effect of the rotating vane is to force the entering water or other fluid to move in a constantly expanding conical stream which hugs the inner face of the conical chamber 11 and thus creates a central vacuum and causes the pump to act to that extent as a suction pump. When the water has reached the greatest expansion and is moving with its greatest speed, it enters the cylindrical portion of the pump chamber where the speed is continued by the non-tapering portions of the vanes and the condition of uniformity is established before the fluid enters the outlet opening 15 to pass out through the delivery pipe 16. The form of bearing shown preserves 100 continually a perfectly tight condition against leakage, since all wear of the conical surfaces is taken up by the spring. 105 110

In Fig. 2 is shown a modification of the device wherein a strong flat spring 30 is fixed to the back of the pulley 22 and bears upon a bushing 31 similar to the bushing 25 at the opposite end. The spring 30 sets into a transverse recess or groove 32 in the head of the bushing 31, and thus causes the latter to revolve with the pulley and shaft. This latter form is appropriate to larger pumps, and can be used with a short shaft 21, lubricated by means of an oil feed pipe 33.

What I claim is—

1. In a machine operating with a fluid 15 under pressure, a chamber having a conical seat and a hollow extension beyond it, a revolvable member having a conical portion fitting said seat, a shaft on said member passing through said extension, a conical seat on the outer end of said extension, a sleeve on said shaft having a conical portion fitting said second seat, and a spring 20 adapted to press both of said conical portions against their respective seats while permitting said shaft and revolvable member 25 to turn, substantially as described.
2. In a machine operating with a fluid under pressure, a chamber having a conical

seat and a hollow extension beyond it, a revolvable member having a conical portion 30 fitting said seat, a shaft on said member passing through said extension, a conical seat on the outer end of said extension, a sleeve on said shaft having a conical portion fitting said second seat, and having an 35 external transverse groove, a driving pulley on said shaft and a spring seated within said groove and abutting against said pulley, substantially as described.

3. In a centrifugal pump, a pump chamber 40 having a seat and an extension beyond it, a revolvable member within said chamber having a portion fitting said seat, a shaft on said member passing through said extension, a suitably seated revolvable bushing on 45 said shaft at the outer end of said extension having a transverse groove, a driving pulley on said shaft, and a spring on said pulley seated within said groove on said outer bushing, substantially as described. 50

In testimony whereof, I affix my signature, in presence of two witnesses.

PAUL DANIEL.
